UNITED STATES PATENT OFFICE.

GEORGE SPENCE, OF TORONTO, ONTARIO, CANADA, ASSIGNOR TO W. J. GAGE & CO.,
LIMITED, OF TORONTO, CANADA, A COMPANY INCORPORATED IN CANADA.

LOOSE-LEAF BINDER.

937,191.

Specification of Letters Patent. Patented Oct. 19, 1909.

Application filed January 2, 1909. Serial No. 470,297.

To all whom it may concern:

Be it known that I, GEORGE SPENCE, of the city of Toronto, in the county of York, in the Province of Ontario, Canada, have invented certain new and useful Improvements 5 in Loose-Leaf Binders, of which the following is the specification.

My invention relates to improvements in loose leaf binders, and the object of the invention is to devise an extremely simple 10 form of binder, which may be readily detachable and which is especially adaptable for school use, although it may be with equal facility adapted for general use and it consists essentially of a bar suitably held in the 15 binding end of the back cover and provided with upwardly extending back sockets, and a central pin with a reduced T-shape head, and a co-acting bar suitably secured in the 20 binding end of the front cover and provided with pins to fit into the sockets, and a revoluble button recessed and provided with a slot slightly larger in size than the cross 25 bar of the T-shape head of the pin in the opposing part, such button being designed to be turned, so that the slot extends cross- 30 wise under the T-shape head to lock the binder, and the parts being otherwise constructed and arranged in detail as herein- after more particularly explained.

Figure 1, is a perspective view of my improved loose leaf binder. Fig. 2, is a longitudinal section through the binding end of the binder. Fig. 3, is an enlarged detail of 35 the bars when secured together. Fig. 4, is an enlarged detail of the bars when separated. Fig. 5 is a sectional detail view.

In the drawings like letters of reference indicate corresponding parts in each figure.

40 A is the lower or back cover of the binder, which has bound into the binding end a bar B having located toward each end the upwardly extending sockets C.

45 D is a pin provided with a tapered and reduced upper end D' having a substantially T-shaped head D² at the top as indicated.

E is a bar, which is suitably secured in the binding end of the front cover and is provided with end pins E', which are designed

to pass into the sockets attached to the opposing bar.

F is a button provided with a centrally recessed portion F' having a slot F² therein, such slot being slightly in excess of the size of the T-shaped head D². The button F is 55 swiveled in suitable bearings F³ in the bar E and is preferably provided with a stop F⁴ to limit the movement of the T-shaped head within the recess F'. Of course, the button F may be formed flat, although the form 60 I have shown is the preferable form.

The paper of the loose leaf binder is provided with three perforations, two to pass over the sockets C and one to pass over the central pin D. The top cover is placed in 65 position by inserting the pins E' into the sockets C, thereby forming a guide to insure that the pin D enters the button F, the slot of which is set to register with the T-shaped head. As soon as the top cover is placed in 70 position with the binding end set as herein-before referred to the button F is turned, so that the slot extends crosswise of the T-shaped head when the binder is locked in position.

Such a binder as I describe is very simple, cheaply made and convenient and adaptable for various purposes in which it is not necessary that the binder should be locked by a key.

75 What I claim as my invention is:

In a loose leaf binder, the combination with the back bar suitably bound to the back cover and provided with end sockets and central stem or pin provided with a reduced 80 end having a T-shaped head, of the top bar provided with pins to co-act with the socket in the lower bar and a suitable button suitably swiveled in the top bar and provided with a slot designed to co-act with the 85 T-shaped head of the pin of the lower bar, and a stop to limit the turning of the button as and for the purpose specified.

GEORGE SPENCE.
